(57) **CLAIM**

The ornamental design for a container with surface ornamentation, as shown and described.

DESCRIPTION

This contains at least one drawing executed in color. Copies of this patent or patent application publication with color drawing(s) will be provided by the Office upon request.

FIG. 1 is an embodiment of a perspective view of our design;

FIG. 2 is an embodiment of a front view of our design;

FIG. 3 is an embodiment of a back view of our design;

FIG. 4 is an embodiment of a left side view of our design;

FIG. 5 is an embodiment of a right side view of our design;

FIG. 6 is an embodiment of a top view of our design;

FIG. 7 is an embodiment of a bottom view of our design;

FIG. 8 is an embodiment of a perspective view of our design exemplified in color;

FIG. 9 is an embodiment of a front view of our design exemplified in color;

FIG. 10 is an embodiment of a left side view of our design exemplified in color;

FIG. 11 is an embodiment of a right side view of our design exemplified in color;

FIG. 12 is an embodiment of a perspective view of our design;

FIG. 13 is an embodiment of a front view of our design;

FIG. 14 is an embodiment of a perspective view of our design exemplified in color; and,

FIG. 15 is an embodiment of a front view of our design exemplified in color.

Broken lines in the drawings are for illustrative purposes only and do not form a part of the claimed design. In FIG. 1, FIG. 2, FIG. 3, FIG. 4, FIG. 5, FIG. 6, FIG. 7, FIG. 12, and FIG. 13 a container with surface ornamentation may be in any color or colors and need not be in a particular color or colors.

**1 Claim, 14 Drawing Sheets
(6 of 14 Drawing Sheet(s) Filed in Color)**
